BRUSH

Per Lindbo, Oslo, Norway, assignor to A/S W. Jordan
Borste & Penselfabrik, Oslo, Norway

Filed June 24, 1971, Ser. No. 156,600

Term of patent 14 years

Int. Cl. D4—02

U.S. Cl. D4—31

FIG. 1 is a perspective side view of a brush,
FIG. 2 is a side elevation,
FIG. 3 is a bottom plan, and
FIG. 4 is a rear elevation.
The opposite side of FIG. 2 is identical to the side shown.

I claim:

The ornamental design for a brush, as shown and described.
